CLOSURE FOR AEROSOL CANS OR THE LIKE

Eugene H. Neupert, Ferguson, Mo., assignor, by mesne assignments, to The Clayton Corporation of Delaware, Inc., St. Louis, Mo., a corporation of Delaware

Filed Oct. 31, 1960, Ser. No. 62,673

Term of patent 14 years

(Cl. D58—26)

FIG. 1.

FIG. 3.

FIG. 2.

FIGURE 1 is a perspective view taken slightly from the top of a closure for aerosol cans or the like, embodying my new design.

FIGURE 2 is a sectional view taken along line 2—2 of FIGURE 1.

FIGURE 3 is a bottom view thereof.

I claim:

The ornamental design for a closure for aerosol cans or like, substantially as shown.
